Tracey L. Clegg

Atty.

UNITED STATES PATENT OFFICE.

THOMAS L. DEE, OF CHICAGO, ILLINOIS, ASSIGNEE TO SULLIVAN MACHINERY COMPANY, A CORPORATION OF MASSACHUSETTS.

CORE DRILL.

Application filed April 30, 1924. Serial No. 710,117.

My invention relates to core drills.

An object of my invention is to provide an improved core lifter for such a drill. Another object of my invention is to provide 5 an improved core lifter mechanism of great elasticity and strength especially adapted to act upon cores of a soft character. A further and more specific object of my invention is to provide an improved core lifter mechanism having great resiliency and one which has a large internal diameter permitting a ready passage of a core therethrough while still being adapted to hold the same firmly in position within the core barrel when 15 the latter is raised from the hole. These and other objects and advantages of my improved mechanism will hereinafter more fully appear.

In the accompanying drawings I have 20 shown for purposes of illustration one form which my invention may assume in practice.

In these drawings,—

Fig. 1 is a central longitudinal sectional view of a core barrel and drill bit which 25 embody my improved core lifter mechanism, the section through the lifter being taken on line 1—1 of Fig. 2.

Fig. 2 is a plan view, partially broken away to facilitate illustration, of my im- 30 proved core lifter.

Fig. 3 is a side elevation of Fig. 2.

In this illustrative construction I have shown, for purposes of illustration, a core barrel 1 threaded as at 2 to a core lifter cas- 35 ing or shell 3, the lower end of which is threadedly connected as at 4 to a core drill bit 5 of a usual form, herein of the rotary diamond type, while the core lifter casing is provided with an internal conical bore 40 6 with the inclined surfaces 7 of which a core lifter, generally designated 8, of im- proved form to be herein more fully de- scribed, is adapted to engage.

In my improved construction the core 45 lifter 8 comprises a plurality of radially spaced wedges 9 of identic construction hav- ing outwardly inclined surfaces 10 formed at the inner lower edges thereof which are adapted to direct the core upwardly through the core lifter. Carried by the inner periphery of these wedges is a radially expand- 50 ing annular sheet metal spring member 11 adapted to grip a core and having great elasticity, the member 11 being rigidly se-

cured thereto as by rivets 13, the heads of 55 which are peened or headed over in counterbores 14 formed in the spring and the outer peripheries of the wedges in such manner as to form a very compact and rigid construction. The lower end of the spring member 11 is herein also spot welded to the wedges as at 15 forming a smooth joint. As shown, the spring member 11 and one of the 60 wedges 9 are split as at 16 in such manner as to permit the ready expansion and con- 65 traction of the core lifter.

While I have in this application specifically described one form which my invention may assume in practice, it will be understood that this form of the same is shown 70 for purposes of illustration and that the invention may be modified and embodied in other forms without departing from its spirit or the scope of the appended claims.

What I claim as new and desire to secure 75 by Letters Patent is:

1. A core lifter comprising separate spaced wedge shaped supporting members, an annular core gripping member, and means for rigidly securing said core gripping member 80 to the inner surfaces of said supporting members.

2. A core lifter comprising separate spaced wedge shaped supporting members, an annular core gripping spring, and means for 85 rigidly connecting said spring to the inner surfaces of said supporting members.

3. A core lifter comprising separate radially spaced wedge shaped supporting members, a radially expansible core gripping 90 spring member, and means for rigidly securing said spring member to the inner surfaces of said supporting members.

4. A core lifter comprising separate spaced wedge shaped supporting members each hav- 95 ing a vertically disposed inner surface, a core gripping spring member, and means for rigidly securing said spring member to the inner surfaces of said supporting members.

5. A core lifter comprising separate spaced wedge shaped supporting members, a split annular spring, and means for rigidly securing each of said supporting members to the outer surface of said spring. 100

6. A core lifter comprising separate spaced wedge shaped supporting members each hav- 105 ing a projecting shoulder formed thereon, an annular split spring, the shoulders on said

- supporting members underlying the lower edge of said spring, and means for securing each of said members to the outer surface of said spring.
5. 7. A core lifter comprising separate spaced wedge shaped supporting members each having an inwardly projecting shoulder formed thereon, an annular core gripping split spring, the shoulders on said supporting members underlying the lower edge of said spring, and means for securing each of said members to the outer surface of said spring.
10. 8. A core lifter comprising separate spaced wedge shaped supporting members each having a reduced inner surface and an inwardly projecting shoulder, a split annular spring member engaging said shoulders, and means for rigidly securing each member to said spring member.
15. 9. A core lifter comprising separate spaced wedge shaped supporting members each having a reduced inner surface and an inwardly projecting shoulder, a split annular spring member disposed adjacent said surfaces and engaging said shoulders, the latter underlying the spring, and means for rigidly securing each member to said spring member.
20. 10. A core lifter comprising separate spaced wedge shaped supporting members, a split resilient core gripping element, and means for rigidly securing each wedge member to the outer surface of said resilient element.
25. 11. A core lifter comprising separate spaced wedge shaped supporting elements 35 each having an inwardly inclined core guiding surface and an inclined outer surface, a split resilient core gripping element, and means for rigidly securing each of said wedge elements to the outer surface of said 40 resilient element.
30. 12. A core lifter comprising separate spaced wedge shaped supporting members each having an inclined external surface, a resilient core gripping member, and means 45 for rigidly securing said core gripping member to the inner surfaces of said supporting members.
35. 13. A core lifter comprising separate spaced wedge shaped supporting members 50 each having an inclined external surface, a radially expandable annular split core gripping spring, and means for rigidly securing said spring to the inner surfaces of said supporting members. 55
40. 14. A core lifter comprising separate spaced wedge shaped supporting members each having an inclined external surface and a vertically disposed inner surface, a resilient split core gripping member, and means for 60 rigidly securing said core gripping member to the inner surfaces of said supporting members.

In testimony whereof I affix my signature.

THOMAS L. DEE.
